[57] CLAIM

The ornamental design for a pipe shoe guide, substantially as shown and described herein.

DESCRIPTION

FIG. 1 is a front perspective view of a pipe shoe guide showing my new design;

FIG. 2 is a rear perspective view thereof;

FIG. 3 is a bottom perspective view thereof; and,

FIG. 4 is a bottom plan view thereof.

The broken line showing of a pipe shoe and a structural beam is for illustrative purposes only and forms no part of the claimed design.
